POWER TRANSMISSION

Edward A. Thompson, Waterbury, Conn., assignor to The Waterbury Tool Company, Waterbury, Conn., a corporation of Connecticut

Application April 1, 1936, Serial No. 72,106

7 Claims. (Cl. 242—75)

This invention relates to power transmissions, particularly to transmissions of the fluid type comprising a pump unit and a fluid motor unit, at least one of which is provided with means for varying its displacement whereby the speed and torque ratios of the power transmissions may be smoothly varied. The invention is particularly adapted for use with a reeling device and has been illustrated as applied to a mechanism 5 of this character although it will be understood that the invention is equally adaptable to other applications. In reeling devices wherein a strip of material is wound upon an arbor in successive layers, the diameter of the reeled material progressively increases as the material is wound on the reel. If the material is fed to the reel at a constant speed, the speed of the reel arbor must be decreased as the diameter of the reeled material increases, and likewise, 10 if a constant tension is maintained on the material being reeled, a progressively increasing torque must be applied to the reel arbor as the reel diameter increases.

Heretofore in reeling devices, such for example as those used for reeling sheet metal into rolls as it comes from the processing equipment, the speed of the reel arbor has been controlled manually or automatically in accordance with the tension or lack of tension maintained in the 15 strip material between the reel and the device which feeds the strip to the reel.

It is an object of the present invention to provide a power transmission and control therefor which will operate to maintain a constant 20 tension on the material being reeled and maintain a constant peripheral speed on the reeled material automatically in accordance with the load on the power transmission.

A further object is to provide a control device 25 for a variable speed power transmission whereby the output speed of the transmission is varied automatically to produce a constant horsepower at varying torques.

Further objects and advantages of the present invention will be apparent from the following description, reference being had to the accompanying drawing wherein a preferred form 30 of the present invention is clearly shown.

In the drawing:

Fig. 1 is a plan view of a power transmission and reeling device embodying a preferred form 35 of the present invention.

Fig. 2 is a section on line 2—2 of Fig. 1.

In the form of the invention illustrated in Fig. 1 a reel 10 is provided for winding strip material 12 on the arbor thereof. The strip material is fed to the reel from a feeding device which is illustrated as a slitting shear 14. The feeding device 14 is driven by a suitable prime mover, for example a variable speed electric

motor 16 through a reduction gear 18. The motor 16 also drives a fluid pump 19 which is of fixed displacement and is illustrated as of the well-known "Waterbury" type. The pump 19 is connected by means of supply and return conduits 20 and 22 to a four-way reverse and bypass valve 24 which in turn is connected by conduits 26 and 28 with a variable displacement motor 30. The fluid motor 30 drives the reel 10 through a reduction gear 32. The motor 10 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590

In operation of the device a strip of material is fed through the feeding device with its end adjacent the arbor of the reel 10 and the end of the strip is suitably fastened to the arbor by a clamping device, not shown.

During this operation the arbor of the reel 10 may be rotated backward if necessary by operating the reverse valve 24 to connect the supply conduit 20 to the conduit 28 which is the return conduit in normal operation, the motor 16 being "inched" for this purpose. With the motor 16 stationary the reverse valve is then shifted to normal operation in which the supply conduit 20 is connected to the conduit 26 and the return conduit 22 is connected with the conduit 28. The motor 16 is then brought up to speed and the strip material 12 is wound on the reel 10. The spring 46 tends to urge the tilting box 34 into the minimum displacement position which tendency is counteracted by pressure existing in the supply conduits 20 and 28.

At the instant the device is started the tension in the strip material 12 is below normal operating value so that as a result the fluid pressure in conduit 26 is low and the spring 46 maintains the tilting box 34 in minimum displacement position. The fluid motor 30 therefore operates the reel at the highest possible speed immediately after starting until the tension in the strip 12 reaches the normal operating value at

which time the pressure in conduit 26 builds up to a value such that the force exerted on the piston 38 may move the stem 36 upwardly and increase the displacement of the motor 30 sufficient to bring the peripheral speed of the reel 10 to the same value as the speed of the strip through the feeding device 14.

Thereafter, as the diameter of the reeled material increases the speed of the motor 30 is decreased by the action of the piston 38. Thus, the displacement of the motor 30 is progressively increased to keep the peripheral speed of the reel at a substantially constant value and to maintain the tension on the strip 12 likewise constant. As soon as the required amount of material is wound on the reel 10, the motor 16 is stopped and the web material cut so that the roll of reeled material may be removed and the reeling cycle is repeated.

It will be noted that the speed of the reel arbor is varied inversely to the change in torque thereon, as the lever arm of the tension force of the strip 12 increases; and that the power operating the reel 10 is therefore maintained constant. Viewed in another light the speed and displacement of the pump 19 are maintained constant and since the displacement of the motor is varied to maintain a constant working pressure in the conduits 20 and 26, the power input to the pump is therefore likewise maintained constant. Small departures from these theoretically constant conditions are of course introduced due to the varying efficiency of the power transmission at different speeds and due to variations in force exerted by the spring 46 under different degrees of compression. These variations may be made small, however, and for practical purposes may be considered negligible.

While the form of embodiment of the invention as herein disclosed, constitutes a preferred form, it is to be understood that other forms might be adopted, all coming within the scope of the claims which follow.

What is claimed is as follows:

- 45 1. A device for reeling strip material comprising in combination a reel, driving means for the reel including a constant delivery fluid pump and a fluid motor driven by the pump, fluid conduits forming supply and return connections between the pump and motor the total resistance of said connections being negligible, and control means for maintaining a constant peripheral tension in the material being reeled including means responsive to the fluid pressure developed by the motor in the supply connection for varying the displacement of the motor, said conduits being arranged to deliver to the motor the full discharge of the pump under all normal conditions of operation.
- 50 2. A device for reeling strip material comprising in combination, a reel, feeding means for the reel, a fixed displacement fluid pump driven at a speed, the ratio of which is constant with respect to the speed of the feeding means, a fluid motor driven by the pump and connected to drive the reel, fluid conduits forming supply and return connections between the pump and motor the total resistance of said connections being negligible, and control means for maintaining a constant tension on the material between the reel and the feeding means, including means responsive to fluid pressure in the supply connection for decreasing the speed of the motor as the diameter of the reeled material increases.
- 55 3. In a fluid power transmission the combina-

tion of a fixed displacement fluid pump, means for driving the pump at a substantially constant speed for delivering fluid at a uniform rate, a variable displacement fluid motor, fluid conduits forming supply and return connections between the pump and motor the total resistance of said connections being negligible, and means responsive to pressure in the supply connection for regulating the displacement of the motor to maintain a substantially constant power output at varying motor speeds and loads.

4. A device for reeling strip material comprising in combination, a reel, means for feeding strip material to the reel, a constant delivery fluid pump unit, a prime mover for driving both the pump and the feeding means, a fluid motor unit operated by the pump, fluid conduits forming supply and return connections between the pump and motor the total resistance of said connections being negligible, and means responsive to pressure in the supply connection for varying the displacement of one of said units to maintain constant fluid pressure on the pump, whereby the tension on the material being reeled is maintained constant.

5. A device for reeling strip material comprising in combination, a reel, means for feeding strip material to the reel, a fixed displacement fluid pump, a prime mover for driving both the pump and the feeding means, a variable displacement fluid motor operated by the pump, and means for varying the motor displacement to maintain constant fluid pressure on the pump, whereby the tension on the material being reeled is maintained constant, and means including a valve for at times reversing the operation of the reel.

6. A device for reeling strip material comprising in combination, a reel, means for feeding strip material to the reel, a fixed displacement fluid pump, a prime mover for driving both the pump and the feeding means, a variable displacement fluid motor operated by the pump, fluid conduits forming supply and return connections between the pump and motor, the total resistance of said connections being negligible, and means for varying the motor displacement to maintain constant fluid pressure on the motor, said means including a second fluid motor for varying the displacement of the first fluid motor and means responsive to changes in fluid pressure developed in said supply connection for causing said second fluid motor to vary the displacement of the first fluid motor in a manner to restore said pressure to a predetermined substantially constant value, whereby the tension on the material being reeled is maintained constant.

7. A device for reeling strip material comprising in combination, a reel, feeding means for the reel, a fixed displacement fluid pump driven at a speed, the ratio of which is constant with respect to the speed of the feeding means, a fluid motor driven by the pump and connected to drive the reel, fluid conduits of negligible resistance forming supply and return connections between the pump and motor the total resistance of said connections being negligible, and control means for maintaining a constant tension on the material between the reel and the feeding means, including means responsive to fluid pressure in the supply connection for increasing the displacement of the motor as the diameter of the reeled material increases.

EDWARD A. THOMPSON.
